UNITED STATES PATENT OFFICE.

OSCAR F. FISCHEDICK AND ALVIN W. KRAHN, OF MILWAUKEE, WISCONSIN.

WASHING-MACHINE.

1,382,636.

Specification of Letters Patent. Patented June 28, 1921.

Application filed October 15, 1917. Serial No. 196,589.

To all whom it may concern:

Be it known that we, OSCAR F. FISCHEDICK and ALVIN W. KRAHN, citizens of the United States, residing at Milwaukee, county of Milwaukee, and State of Wisconsin, have invented new and useful Improvements in Washing-Machines, of which the following is a specification.

Our invention relates to improvements in washing machines, and pertains especially to that class of washing machines in which the clothes are allowed to drop from side to side within a tilting drum partially filled with cleansing fluid.

The object of our invention is to provide means for applying light suction to the clothes preparatory to dropping them from one side of the drum to the other, thereby partially withdrawing water from the meshes of the fabric and also retaining the clothes in position until the oscillation of the drum has carried them to a higher level than they would otherwise attain. A further object of our invention is to provide means whereby the clothes may be subjected to the impact of a column or quantity of water moving against them from beneath immediately after or simultaneously with the movement of the clothes to the lower side of the drum after having been elevated, as above described. A still further object of our invention is to provide means whereby the major portion, or at least a large portion, of the water within the drum may follow the peripheral wall of the drum when the latter is oscillated, thereby relieving the drum from the strains or shocks which are frequently found to be excessive in washing drums where the water and the clothes are allowed to drop from one side to the other across a shelf disposed along the chord of a segment of the drum. Further, our object is to simplify the construction and increase the efficiency of washing drums of the above mentioned type.

In the drawings:—

Figure 1 is a side elevation, partly in vertical section, of a washing drum embodying our invention.

Fig. 2 is a cross sectional view of the same showing the driving mechanism in elevation.

Fig. 3 is a plan view of the separating shelf or partition screen across which the clothes are dropped during the washing operation.

Fig. 4 is a sectional view, drawn on line 4, 4 of Fig. 3.

Like parts are identified by the same reference characters throughout the several views.

The general construction of the frame A and drum B, together with the door C through which the clothes are inserted and removed, may be assumed to be of any ordinary type. The drum B is supported from the frame A by trunnions b, one at each end of the drum. Motion to oscillate the drum is derived from a motor D, the shaft D' of which transmits an oscillatory movement to the drum through the worm E, worm wheel E', shaft F, crank wheel F' and connecting rod f. A beveled gear wheel G may be mounted on the side of the worm wheel E' in a position to transmit motion to a wringer operating shaft H through a beveled pinion H'. Clutch members I and I' of ordinary type may be employed to connect and disconnect crank wheel F' for rotation with the shaft F, crank wheel F' being loose on the shaft, and clutch member I being splined thereto and shifted into and out of engagement with clutch member I' by means of a lever J.

Within the drum at one side of its axis we provide a partition member in the form of a shelf K, the central portion of which is provided with an undulation K' parallel with the axis of the drum and depressions K'' also parallel with the axis of the drum extend along each side of the upwardly curving undulation K'. The portions L between the depressions K'' and the peripheral wall of the drum comprise a perforate screen in whole or in part. This screen may be formed of wire netting, preferably of non-corrosive material. The shelf or partition extends across the drum substantially along the chord of a segment or arcuate portion of the drum, which normally constitutes the bottom portion of the drum. The central or undulatory portion of the shelf or partition is preferably imperforate.

The shelf or partition above described may be secured in position within the drum by means of brackets M and M' secured to the end wall of the drum and the under surface of the shelf respectively. The brackets M' are preferably formed to slide along the under surface of the shelf, and are provided with knobs or projections N exposed in slots N' formed in the end portions of the shelf, whereby these bracket members M' may be moved into and out of interlocking

engagement with the bracket members M, the member M' serving as latches.

By employing the latches or brackets M', and providing means whereby they may be actuated from the space above the shelf, it is obvious that this shelf or partition can be removed and replaced as often as may be desired, either for repairs or for the purpose of cleansing that portion of the drum 10 underneath the shelf.

In operation, the drum will be partially filled with water, sufficient water being preferably used to substantially cover the shelf when the latter is in the position shown in 15 Fig. 2. The particular amount of water is however not material, except that it is desirable that the drum be not filled more than half full of water.

The clothes and also the water, if desired, may be inserted in the drum through the doorway, after which the door C will be closed and the motor started to oscillate the drum upon its trunnions b. When the drum oscillates in one direction the clothes will 25 drop upon the screen L near one margin of the partition or shelf, and when the drum oscillates in the other direction these clothes will be lifted by the shelf until the inclination becomes such as to cause them to drop 30 across the shelf to and upon the screen L near the other margin thereof.

The clothes, if present in the drum in normal quantity, tend to cover the screen L and prevent free passage of water and air into 35 the space beneath the shelf on the upwardly moving side. This space, however, is full of water, or substantially full of water, when the drum is in the position indicated in Fig. 2, and the weight of this water 40 tends to cause it to pass through the screen L on the downwardly moving side of the drum, thereby creating a light suction which draws water, and eventually air, through the clothes on the upwardly moving side. 45 This suction, although light and insufficient to prevent the clothes from dropping as the drum approaches the limit of its oscillatory movement, is, nevertheless, very effective in removing the dirt from the fabric, since the 50 water entrained in the fiber of the fabric is in direct contact with the dirt and carries the dirt with it when thus withdrawn by suction from the fabric.

When the clothes are carried to a sufficient elevation to allow their weight to cause them to drop from the screen on the upwardly moving side, they will, of course, pass downwardly to the screen on the lower side and in dropping will strike upon the 55 undulation K'. The impact of the clothes upon this undulation is also effective in dislodging particles of foreign matter from the fabric.

The clothes received upon the lower screen 60 L will not only be churned in the water,

which simultaneously drops over the shelf, but will also be subjected to upwardly moving streams of water from the space beneath the shelf. These upwardly moving streams tend to lift the clothes and separate the pieces and folds of fabric from each other. This movement of the water through the clothes therefore not only operates to carry the dirt away from the fiber, but to separate the pieces of fabric in such a manner that the particles of foreign matter may be easily dislodged and removed from the mass of clothing on the screen.

Owing to the fact that a large portion of the water passes underneath the shelf during the oscillation of the drum, it is obvious that the walls of the drum are not subjected to heavy shocks, such as would be exerted if all the water was permitted to rush across the top of the shelf from one side of the drum to the other. This enables us to employ a lighter and cheaper structure than would otherwise be required, and materially increases the durability of the drum.

We claim:

1. A cylindrical washing drum supported to oscillate about the horizontal axis of the drum, and having an interior clothes supporting partition below its axis, the central portion of which is arched and imperforate 95 and continuous with the marginal side portions from one end of the drum to the other, and the side portions of which are provided with a multitude of small openings of such number and capacity as to permit a substantially free flow of water underneath the partition from one side to the other, along the interior surface of the peripheral wall of the drum, while preventing articles of clothing from passing to the space beneath the 100 partition.

2. A horizontally disposed washing drum mounted to oscillate about its axis, and having the lower portion thereof interiorly subdivided by a partition centrally arched and imperforate along a line parallel with and below the axis of the cylinder, and having marginal portions at the respective sides of the centrally arched portion, composed of wire netting adapted to permit a substantially free flow of water underneath the partition along the inner surface of the peripheral wall of the drum, and also adapted to prevent clothing from passing underneath the partition, said imperforate centrally 110 arched portion being smooth surfaced, and adapted to retain the clothing upon one of the marginal portions until the drum has been oscillated sufficiently to allow the clothes to fall across said arched portion to 115 the other side, and to allow the clothes to so fall in a quick movement, coincidently with the forcible rush of water through the depressed marginal portion from below the partition.

3. A horizontally disposed cylindrical washing drum mounted to oscillate about its axis, and having the lower portion thereof 5 interiorly subdivided by a partition centrally arched and imperforate along a line parallel with the axis of the cylinder, and having marginal portions at the respective sides of the centrally arched portion composed of wire netting adapted to permit a 10 substantially free flow of water underneath the partition along the inner surface of the peripheral wall of the drum, and also adapted to prevent clothing from passing underneath the partition, said partition being detachably secured to the wall of the drum, 15 whereby it may be removed to facilitate cleansing the drum, and subsequently replaced and secured in position, all portions of said partition being relatively fixed in 20 relation to each other and to the walls of the drum.

4. A clothes supporting element for use in

a tilting drum washing machine comprising a plate having an arched imperforate central portion and a foraminous clothes supporting portion on each side of said central portion extending for the greater part of the length of the plate, said portions being relatively disposed so that when the plate is positioned in a drum the foraminous portions will be on opposite sides of the axis of the drum and will alternately support the clothes. 25

5. The element specified in claim 4, said plate having means thereon for detachably 30 securing the same in fixed position within a washing drum.

In testimony whereof we affix our signatures in the presence of two witnesses.
